UNITED STATES PATENT OFFICE.

GEORGE J. WEBER, OF KANSAS CITY, MISSOURI.

GAS-ENGINE.

SPECIFICATION forming part of Letters Patent No. 449,507, dated March 31, 1891.

Application filed April 8, 1890. Serial No. 347,088. (No model.)

To all whom it may concern:

Be it known that I, GEORGE J. WEBER, of Kansas City, in the county of Jackson and State of Missouri, have invented certain new 5 and useful Improvements in Gas-Engines, of which the following is a full, clear, and exact description, reference being had to the accompanying drawings, forming a part of this specification.

10 This application is for an improvement on the invention set forth in my application filed July 24, 1889, Serial No. 318,596.

15 My invention relates to an improvement in gas-engines; and my invention consists in features of novelty hereinafter described, and pointed out in the claims.

20 Figure I is a perspective of my improved engine. Fig. II is a section showing the exhaust-valve and the operation thereof. Fig. III is a detail showing the gas-supply valve and its operating device. Fig. IV is an enlarged detail of the weighted arm for operating the gas-supply valve. Fig. V is an enlarged sectional view of the rotary ignition 25 valve and bonnet.

25 Referring to the drawings, 1 represents the power-cylinder in which works the piston 2.

30 3 represents the piston-rod, which is tapped into a head 4 and on which there is a jam-nut 5, by which means the rod can be adjusted in the head. The head 4 is pivoted to the piston 2 by means of a hollow shaft 6. The shaft 6 has a hollow portion 7 for holding oil or other lubricant.

35 8 represents openings leading from the hollow shaft into the head 4 for the passage of the lubricant for the lubrication of the head in its bearing.

40 The shaft 6 has an internal screw-thread 9, in which a plug 10 engages. The plug 10 is screwed into the hollow shaft step by step as often as may be desired in order to force the lubricant out through the openings 8.

45 11 represents a tube in the wall of the cylinder having communication with the shaft 6 and having a plug 12 at its outer end. By the removal of the plug 12 access may be had to the plug 10.

50 The upper end of the piston-rod 3 is journaled to crank-arms 13 on the drive-shaft 14.

15 represents a double right and left screw located near one end of the drive-shaft 14, in

which engages swivel 15½ on the upper end of a rocking lever 16. The rocking lever 16 is fulcrumed to the frame of the cylinder by 55 a bracket 17. The lower end of the rocking lever has a shaft 18 attached thereto, said shaft having friction-rollers 19 20 journaled thereon.

21 represents the chamber into which the gas first enters on its way to the cylinder to be fired. It then passes from the chamber 21, through an opening 22, into the firing-chamber 23, from whence it passes through an opening 24 into the cylinder proper ready 60 to be fired.

25 represents the gas-supply valve, which is located in the firing-chamber 23 and which is secured to a vertical rod 26, the rod 26 extending up through the chamber 21 and having a coil-spring 27 thereon for holding the valve 25 up to its seat while the same is in its normal position.

28 represents a vertically-adjustable collar near the upper end of the rod 26, said collar 75 being adjusted by a jam-nut 29. The upper end of the collar forms a shoulder 30.

31 represents an arm pivoted at 32 to the frame, said arm having a V-shaped projection 33 on its upper side, against which the friction-roller 20, attached to the rocker-shaft 16, impinges at stated intervals governed by the double screw 15 on the drive-shaft.

34 represents a pendent arm pivoted at 35 in a mortise 36 of the arm 31, and also has a 85 V-shaped projection against which the roller 20 also bears at stated intervals.

38 represents a weight, which is an integral part of the arm 34, and which holds said arm normally in the position shown in dotted 90 lines, Fig. IV.

As the roller 20, by the action of the rocker arm 16, comes in contact with the projection 33 on the arm 31, and in contact with the projection 37 on the arm 34, the arm 31 will 95 be depressed, and the arm 34 will be thrown into the position shown in Fig. IV, at which time the lower end of the arm 34 will come in contact with the collar 28 on the upper end of the rod 26, which operates the gas-supply valve, said rod and valve being thus depressed and a fresh supply of gas admitted to the cylinder.

It is desired at times not to admit a fresh

supply of gas at every depression of the arm 31, as the engine might be driven faster than is necessary for the amount of work it is required to do. It is obvious that for economic working and safety the admission of gas and the time of firing the same should be controlled by the engine-governor.

39 represents the governor, which is made in the usual form. To the governor is attached one end of a rod 40, said rod extending down to and connected with a crank 41 on a shaft 42, said shaft being journaled in the wall of the cylinder, as shown at 43. On the opposite end of the shaft 42 is a dog 44. It will be seen when a high speed is obtained the governor will rise, and in so doing will raise the rod 40, operating the crank 41, and will thus throw the dog 44 forward a sufficient distance to prevent the arm 34 from engaging the collar 28, and thus prevent a fresh supply of gas being admitted until the speed of the engine has been reduced. As a means to control the governor I place a pulley 45 on the drive-shaft, around which travels a belt 46, said belt then passing over pulleys 47, journaled on arms 48, and thence around a pulley 49, situated beneath the governor. The arms 48 are pivoted at 50 to a collar 51, and have bearing-points 52 and 53 $\frac{1}{2}$. The collar 51 has a pin 53 working in a slot 54. The tension of the belt 46 will hold the pulley 47 and arm 48 in the position shown in Fig. III; but if said belt should break and said balls cease to revolve, then the engine would speed beyond requirements.

With my device if the belt breaks the arm 48 will be released from belt-tension, and will be free to ascend, as spring 55 bears against collar 51, carrying it and pin 53 upward. Then the inner end of arm 48 bears against the support at 53 $\frac{1}{2}$. As the collar 51 ascends, pin 53 presses against collar 56 on the rod 40, which causes the governor to act same as if it were running.

45 57 represents an opening in the cylinder, through which the exhaust passes after the charge of gas has been fired and its force expended on the piston. The exhaust passes from the opening 57 into the chamber 23 and then through valve-opening 59 into a chamber 60, and thence out through port 61.

62 represents the exhaust-valve located in the chamber 23 on a rod 63, said valve closing the opening 59 when it is in its normal position. This rod extends up through the chamber 60, and has a coil-spring 64 located thereon for holding the valve 62 closed.

65 represents an arm pivoted at 66 to the engine-frame, said arm being depressed at stated intervals by the roller 19 on the lower end of the rocking lever 16 rolling against a projection 67 on the arm, causing an adjustable collar 68 on the under side of the lever to come in contact with the upper end of the valve-rod 63, depressing the same and thus opening the exhaust-valve 62. The collar 68

is secured to a screw 69 on the under side of the lever, and is set at any desired point by a jam-nut 70, to regulate the amount of valve-opening and to compensate for wear.

71 represents the ignition-tube, which has a central opening 72, leading into the chamber 23 through a bonnet 72 $\frac{1}{2}$, which is screwed into the wall of the chamber. The opening 72 is closed at the intervals between firing the charges of gas by a disk 73 within the chamber 23, having a series of rotating valves 74. The stems 75 of the valves 74 are held in openings 76 in the disk and have coil-springs 77 at their rear ends in said openings, by which means they are at all times held firmly against the bonnet 72 $\frac{1}{2}$ in the wall of the chamber 23. The upper one of the valves 74 and its spring 76, however, have no function other than to counterbalance the pressure of the spring 76 on the opposite side of the disk 73, so that the pressure of the latter spring cannot cant the disk; but nevertheless in the event the lower valve becomes damaged the disk 73 may be turned around and the now upper valve employed to close the port 72.

78 represents an opening extending through the disk 73, through which the flame shoots from the ignition-tube when a charge of gas is being fired.

The disk 73 is secured to a shaft 79, said shaft extending through the bonnet 72 $\frac{1}{2}$, and having a coil-spring 80 thereon for holding the disk tightly against the bonnet. To the outer end of the shaft 79 is secured a crank-arm 81, having a rod 82 pivoted at its outer end.

83 represents a coil-spring on the rod 82, by which means the disk 73 is held in its normal position, so that one of the lower ones of the valves 74 will close the opening 72 leading from the ignition-tube. On the upper end of the rod 82 is an adjustable collar 84 for lengthening or shortening said rod to regulate the time of firing.

85 represents a jam-nut for locking the collar.

It will be seen that as the arm 31 is depressed its outer end 86 will depress the rod 82 on which it rests, and by depressing the same will cause the disk 73 to rotate to a certain extent, thus causing the lower valve 74 to pass from the opening 72 and permit any burned product contained in the tube to pass out into the chamber 23. The ignition-tube 120 is heated by a jet or other means, and as the roller 20 travels back over the projection 33 the rod will be again depressed, opening the valve and permitting the gas to enter the tube 71, where it is ignited and shoots back into the chamber 23, igniting the full charge of gas.

87 represents an opening in the bonnet 72 $\frac{1}{2}$, through which the disk 73 may be lubricated.

88 represents a water-space surrounding the cylinder, in which I place sections of wood or other yielding substance 89, which, if the water should freeze, will give or yield—that

is, become compressed under the pressure of the ice—and thus obviate the breaking of the walls of the cylinder.

50 represents a water-space surrounding the bonnet $72\frac{1}{2}$, in which water may be circulated to prevent the bonnet from becoming overheated.

I claim as my invention—

1. In a gas-engine, the combination of the drive-shaft 14, double right and left hand screw 15 on the shaft, pivoted rocking lever 16, having its upper end engaging the screw, and having friction-rollers on its lower end for the purpose of operating valve-gear, substantially as described, and for the purpose set forth.

2. In a gas-engine, the combination of the main shaft 14, double screw located thereon, rocking lever engaging the double screw at its upper end, friction-rollers journaled to the lower end of the rocking lever, and pivoted arms with which said rollers engage to operate valve-gear.

3. In a gas-engine, the combination of the main shaft 14, double screw on the shaft, rocking lever engaging the double screw at its upper end, friction-roller 20, journaled to the lower end of the rocking lever, and a pivoted arm 31, having a V-shaped projection 33, against which the roller bears in order to depress the same, substantially as described, and for the purpose set forth.

4. In a gas-engine, the combination of the rocking lever, means for operating the same, roller 20 on the lower end of the rocking lever, pivoted arm 31, and a weighted arm 34, pivoted to the arm 31 for the purpose of operating valve-gear, substantially as described, and for the purpose set forth.

40 5. In a gas-engine, the combination of the rocking lever, means for operating the same, roller 20 on the lower end of the rocking lever, pivoted arm 31, V-shaped projection 33 on the arm 31, weighted arm 34, pivoted to the arm 31, projection 37 on the arm 34, against which the roller 37 bears in order to throw the lower end of the arm 34 into contact with a collar 28 on the rod 26 of the gas-admission valve 25, in order to depress said rod and valve and to admit a charge of gas, substantially as described, and for the purpose set forth.

6. In a gas-engine, the combination of the pivoted arm 31, means for depressing the same, weighted arm 34, pivoted to the arm 31, means for vibrating the arm 34 and throwing it into contact with an adjustable shoulder 28 on a rod 26, said rod being connected to a gas-supply valve 25, and a spring on said rod for holding the valve in its closed position, substantially as described, and for the purpose set forth.

7. In a gas-engine, the combination of the weighted arm 34, having a pivoted support, valve-rod 26, having an adjustable collar 28, and a pivoted dog 44, which may be automat-

ically thrown into position to prevent the arm 34 from engaging the collar 28, substantially as described, and for the purpose set forth.

8. In a gas-engine, the combination of the 70 arm 34, having a pivoted support, valve-rod 26, having an adjustable collar 28, a dog 44, secured to a pivoted shaft 42, crank-arm 41 on said shaft, and a rod 40, connecting the crank-arm 41 with the engine-governor, whereby the dog 44 may be automatically thrown into position to prevent the arm 34 from engaging the collar 28 on the valve-rod 26, substantially as described, and for the purpose set forth.

9. In a gas-engine, the combination of the governor 39, dog 44, rod 40, connecting the dog with the governor, collar 51 on the governor-frame having a pin 53, and a spring 55 for raising the collar 51 and causing the pin 85 53 on the same to engage a collar 56 on the rod 40, causing said rod to rise and thus operate the dog 44, substantially as described, and for the purpose set forth.

10. In a gas-engine, the combination of the 90 collar 51 on the governor-frame, spring 55 for raising the collar, lever 48, pivoted to the collar, pulley 47 on the outer end of the lever, pulley 49 on the governor-frame, pulley 45 on the engine's drive-shaft, and a belt 46, 95 traveling on all said pulleys, whereby the tension of the same on the pulley 47 will cause the lever 48 to hold the collar 51 in its normal position, substantially as described, and for the purpose set forth.

11. In a gas-engine, the combination of the pivoted arm 31, means for depressing the same, a rotary disk 73, situated in the chamber 23, ignition-valves 74, located in the disk, and an adjustable rod 82, connecting the disk 105 with the arm 31, whereby the depression of said arm will cause said disk to rotate, substantially as described, and for the purpose set forth.

12. In a gas-engine, the combination of the 110 main shaft, the ignition-tube, the disk 73, secured to a shaft 79, valves 74, located in said disk for closing said tube, arm 81, secured to the opposite end of the shaft 79, a spring 80, interposed between the arm 81 and the shaft-bearing, and a pivoted arm connected to arm 81 and adapted to receive motion from the main shaft, substantially as described, and for the purpose set forth.

13. In a gas-engine, the combination of the 120 bonnet $72\frac{1}{2}$, having an opening 72 for the admission of gas to a tube 71, a rotary disk 73, having an opening 78, and valves 74 in the disk for closing the opening 72, substantially as described, and for the purpose set forth.

14. In a gas-engine, the combination of the bonnet $72\frac{1}{2}$, valve secured to the bonnet, and an opening 90, surrounding the bonnet, said opening being for the circulation of water to prevent the same from becoming overheated, 130 substantially as described, and for the purpose set forth.

15. In a gas-engine, the combination of the bonnet 72¹₂ and a valve secured to the bonnet, said bonnet having an opening 87 for the lubrication of said valve, substantially as described, and for the purpose set forth.
16. In a gas-engine, the combination of the exhaust-valve 62, rod 63, connected to said valve, spring 64 on the rod for holding the valve in its closed position, pivoted arm 65, having a projection 67 on its upper side, and an adjustable collar on its under side, whereby when said arm 65 is depressed said rod will be depressed and the exhaust - valve opened, substantially as described, and for the purpose set forth.

17. In a gas-engine, the cylinder having openings within the same for the circulation of water and a yielding substance placed in said openings, whereby if the water should freeze such substances would yield and thus prevent the cylinder from breaking, substantially as described, and for the purpose set forth.

GEORGE J. WEBER.
